UNITED STATES PATENT OFFICE.

HORACE GREELEY TURNER, OF MONTREAL, CANADA.

PULP WASHER OR CONDENSER.

SPECIFICATION forming part of Letters Patent No. 772,192, dated October 11, 1904.

Application filed November 13, 1903. Serial No. 181,093. (No model.)

To all whom it may concern:

Be it known that I, HORACE GREELEY TURNER, of the city of Montreal, in the district of Montreal and Province of Quebec, Canada, have invented certain new and useful Improvements in Washers or Condensers; and I do hereby declare that the following is a full, clear, and exact description of the same.

My invention relates particularly to continuously-operating apparatus for use in washing or condensing pulp or any other granular or fibrous or other finely divided or disintegrated substances; and it has for its object to provide a washer or condenser wherein when the apparatus is used as a washer the substance will be washed repeatedly through a series of stages, in each of which the water in which the substance is washed is drawn off and the fresh water supplied in variable quantity and wherein the resistance to the substance flowing through each stage is adjusted.

The invention may be said, briefly, to consist of a vertical washing-chamber comprising a series of superimposed stages, each of which has a screening-wall through which the water, after having washed the pulp, is drawn off, while such water drawn off is compensated by fresh water supplied through a valve-controlled inlet. A series of doctors, preferably spring-actuated, are adapted to keep the washed pulp from adhering to the screening-wall, and such doctors are kept clear of pulp by jets of water, while the resistance to the water flowing through the apparatus, and consequently the depth of water therein and the pressure thereof, is regulated by an outlet adjustable to different levels, and the adjusted depth and pressure are maintained constantly by an automatically-variable discharge-valve.

For full comprehension, however, of my invention reference must be had to the accompanying drawings, forming a part of this specification, in which similar reference characters indicate the same parts, and wherein—

Figure 1 is a side elevation of a pulp-washer constructed according to my invention. Fig. 2 is a longitudinal vertical sectional view thereof, taken on line A A, Fig. 1. Fig. 3 is a horizontal sectional view taken on line B B, Fig. 2, and with the series of openings in the

horizontal partitions shown in dotted lines; and Fig. 4 is a horizontal sectional view of the automatically-variable discharge-valve.

A circular tank *b* has a screening member in the form of a cylinder *c* therein, preferably constructed of perforated sheet metal and extending from within a short distance of the bottom thereof to a point within a short distance of the top. The lower end of this screening-cylinder has a bottom *d*, to which the lower end of the driving-shaft *e* is rigidly connected, as at *f*, and the upper end has a solid head *d'* with an opening *d''* to prevent a vacuum forming in the interior of the cylinder, while an annular bearing-block *g* of truncated conical form upon the under side of this bottom rests in a correspondingly-formed annular bearing-seat *g'* upon the bottom of the tank, thereby guiding the lower end of the screening member and centralizing it when it is inserted. A flexible shield in the form of an annular apron is fastened to the conical bearing-block *g* and hangs downwardly over the bearing-seat *g'* and keeps the pulp from leaking through the bearing-faces, but allows the water to pass. A discharge-pipe leads from the bottom of the tank and communicates at its upper end with the interior of the screening-cylinder (through the opening in the bearing-block and its seat) and at its lower end through a T with one end of a pipe length *h*, the opposite end whereof has a loose-joint elbow *h'* thereon, having the main discharge-pipe *j* mounted rigidly in the other end thereof, such discharge-pipe, through the medium of the elbow, being adjustable to different angular positions to vary the height of its discharge end, and consequently adjust the resistance to the substance flowing through the screening-cylinder. The automatically-variable discharge-valve is connected to the lower end of the T.

A series of horizontal annular partitions *m* are disposed a short distance above one another within the tank, and with the wall of the tank and the screening member they form a series of stages in each of which the pulp passing through the tank receives an independent washing. These plates are of a width to extend from within contact with the interior of

the tank to within close proximity to the screening-cylinder, the spaces between the inner edges of such partitions and the screening-cylinder being closed by flexible packing-rings *n*, while each partition is provided with an opening *o*, the openings of the series of partitions being set in different angular positions, and the corresponding side edge of each opening has a vertical partition *p*, extending upwardly to the opposite side edge of the opening in the annular partition next above it. The lowermost annular partition is supported on a ring *q*, secured rigidly to the inside of the tank a short distance above the lower end of the screening-cylinder, and the other annular partitions are supported upon distance-pieces *r*, each resting upon a partition and supporting the one next above it.

A series of doctors *s* are pivotally connected at one side edge to the annular partitions between which they extend, and a series of springs *t* yieldingly maintain these doctors in bearing relation with the screening-cylinder.

A series of perforated annular pipes *u* of preferably upwardly progressively decreasing capacity are located one in each stage, and they are of sufficient diameter to encircle the stage near the outer periphery thereof. These annular pipes are fed from a common feed-pipe *v* through a series of branches, each controlled by a valve *w*, and a series of nozzles *y* communicate at one end with the perforated pipes and are disposed to direct a jet diagonally upon the doctors to prevent the collection of pulp on the latter. The object of the diagonal arrangement of the jets is to cause it to agitate the thickened stock and accelerate the flow. An intake-pipe *2* for the pulp to be washed leads to the lowermost stage, and an exit-pipe *3* for the washed pulp leads from the topmost stage, the intake-pipe being controlled by a valve *4*.

The branch pipes which connect the common water-feed pipe to the annular perforated pipes are connected to such annular perforated pipes by plug-joints *5* to allow the perforated pipe or sprinklers to be easily removed. A series of wedges *7*, driven between the interior of the tank and the sides of the sprinkler-pipes opposite to the common supply-pipe, keep the sprinkler-pipes in place, and the upper end of the driving-shaft is provided with a driving-pulley *10*, and such shaft bears and is localized in a vertical opening or a bearing-box in a transverse girder *12*, supported upon the top of the tank, while an oil-tray *13*, located beneath the girder and encircling the shaft, prevents the drip of oil from the bearing-box or pulley reaching the washer.

The automatically-variable discharge-valve connected to the lower end of the *T*, as before mentioned, consists of a short sleeve *14*, having a series of longitudinal valvular slots or ports *15*, and a valve-disk *16* within this slotted sleeve is supported by an expansile

helical spring *17*, supported in turn upon a cap *18*, closing the lower end of this sleeve.

The valve controlling the intake-pipe is opened and the pulp-laden water is allowed to flood the tank. In so doing the pulp-laden water must first fill the first stage and then rise through the opening in the first annular partition into the second stage, around which it is made to circle until it comes in contact with the vertical partition, when it will rise through the next opening to the third stage, and so on until it reaches the topmost stage. As it flows around each stage the water will flow through the screening-cylinder to the water-discharge pipe, which it floods, and simultaneously sufficient fresh water will be sprayed into the stage to maintain the original or any desired consistency, thus causing a change of water in each stage, and consequently a progressive step-by-step washing of the pulp. As the washing-water flows from the different stages into the screening-cylinder the level in the latter will gradually rise until it overflows the discharge end or mouth of the adjustable discharge-pipe. By adjusting this discharge-pipe to different angular positions the working head is varied, and the degree to which it is set is uniformly maintained by the automatically-variable discharge-valve, which increases and diminishes its discharge capacity as the pressure due to the height of water in the screening-cylinder increases or diminishes relatively to the degree to which it is set.

My improved construction enables the screening-cylinder, which constitutes one of the walls of each stage, to be readily removed for repairs or cleaning.

The automatically-variable discharge-valve may be dispensed with under certain circumstances and the adjustable pipe alone used for the discharge, or vice versa, or the fresh-water supplies partially or wholly cut off and the apparatus utilized as a condenser and other changes made in the precise arrangement or construction of the parts without departing from the spirit of my invention.

What I claim is as follows:

1. A pulp washer or condenser consisting of a vertical cylindrical tank, a vertical cylindrical screening member within said tank, means for rotating such screening member, a series of horizontal partitions dividing the space between such cylinders into a vertical series of stages, means for effecting a communication between the stages of such series, means for causing the pulp to circle around each stage before passing therefrom to the next, a discharge-duct communicating with the interior of the screening member, a supply-duct for the pulp to be washed leading to the lower end of the tank, and a discharge-pipe leading from the upper end of the tank.

2. In a pulp washer or condenser comprising a vertical series of washing stages and

means for causing the pulp to be washed to flow through such stages from the bottommost to the topmost thereof, means for causing the pulp to be washed repeatedly when it flows through such stages, and means for adjusting the pressure in such pulp-washer.

3. In a pulp washer, or condenser means for adjusting the pressure of the washing fluid therein.

10 4. In a pulp washer or condenser, means for adjusting the pressure of the washing fluid therein, and means for uniformly maintaining the pressure when adjusted.

15 5. A pulp-washer consisting of a vertical cylindrical tank, a vertical cylindrical screening member within said tank, a series of horizontal partitions dividing the space between such cylinders into a vertical series of stages, means for effecting a communication between 20 the stages of such series, means for causing the pulp to circle around each stage before passing therefrom to the next, a discharge-duct communicating with the interior of the screening member, a supply-duct for the pulp 25 to be washed to the lower end of the tank, and a discharge-pipe leading from the upper end of the tank.

30 6. A pulp-washer consisting of a vertical cylindrical tank, a vertical cylindrical screening member within said tank, a series of horizontal partitions dividing the space between such cylinders into a vertical series of stages, means for effecting a communication between the stages of such series, means for causing 35 the pulp to circle around each stage before passing therefrom to the next, a discharge-duct communicating with the interior of the screening member, such duct having its discharge end vertically adjustable, a supply-40 duct for the pulp to be washed leading to the lower end of the tank, and a discharge-pipe leading from the upper end of the tank.

45 7. A pulp-washer consisting of a vertical cylindrical tank, a vertical cylindrical screening member within said tank, a series of horizontal partitions dividing the space between such cylinders into a vertical series of stages, means for effecting a communication between the stages of such series, means for causing 50 the pulp to circle around each stage before passing therefrom to the next, a discharge-duct communicating with the interior of the screening member, and having an automatically-variable valve controlling same, a supply-55 duct for the pulp to be washed leading to the lower end of the tank; and a discharge-pipe leading from the upper end of the tank.

55 8. A pulp-washer consisting of a vertical cylindrical tank, a vertical cylindrical screening member within said tank, a series of horizontal partitions dividing the space between such cylinders into a vertical series of stages, means for effecting a communication between the stages of such series, means for causing 60 the pulp to circle around each stage before

passing therefrom to the next, a discharge-duct communicating with the interior of the screening member, and having an automatically-variable valve controlling same, such duct having its discharge end vertically adjustable, 70 a supply-duct for the pulp to be washed leading to the lower end of the tank, and a discharge-pipe leading from the upper end of the tank.

9. A pulp-washer consisting of a vertical cylindrical tank, a vertical cylindrical screening member within said tank, means for rotating such screening member, a series of horizontal partitions dividing the space between such cylinders into a vertical series of stages, 80 means for effecting a communication between the stages of such series, means for causing the pulp to circle around each stage before passing therefrom to the next, a discharge-duct communicating with the interior of the screening member, such duct having its discharge end vertically adjustable, a supply-85 duct for the pulp to be washed leading to the lower end of the tank, and a discharge-pipe leading from the upper end of the tank. 90

10. A pulp-washer consisting of a vertical cylindrical tank, a vertical cylindrical screening member within said tank, means for rotating such screening member, a series of horizontal partitions dividing the space between such cylinders into a vertical series of stages, 95 means for effecting a communication between the stages of such series, means for causing the pulp to circle around each stage before passing therefrom to the next, a discharge-duct communicating with the interior of the screening member, and having an automatically-variable valve controlling same, a supply-100 duct for the pulp to be washed leading to the lower end of the tank, and a discharge-pipe 105 leading from the upper end of the tank.

11. A pulp-washer consisting of a vertical cylindrical tank, a vertical cylindrical screening member within said tank, means for rotating such screening member, a series of horizontal partitions dividing the space between such cylinders into a vertical series of stages, means for effecting a communication between the stages of such series, means for causing 110 the pulp to circle around each stage before passing therefrom to the next, a discharge-duct communicating with the interior of the screening member, and having an automatically-variable valve controlling same, such duct having its discharge end vertically adjustable, 115 a supply-duct for the pulp to be washed leading to the lower end of the tank, and a discharge-pipe leading from the upper end of the tank. 120

12. In a pulp-washer the combination with 125 a rotary member of a doctor bearing upon such member and means directing a jet of water upon such doctor.

13. In a pulp-washer the combination with 130 a tank and a rotary screening member therein

- of a series of doctors bearing upon such screening member and means directing a jet of water upon such doctors.
14. In a pulp-washer the combination with 5 a tank and a rotary screening member therein of a series of doctors bearing upon such screening member and means directing a jet of water diagonally upon such doctors.
15. In a pulp-washer the combination with 10 a tank containing a washing fluid and a rotary screening member therein, of a doctor submerged in the washing fluid in said tank, and means for causing said doctor to bear upon the screening member.
16. In a pulp-washer the combination with 15 a tank and a rotary screening member therein, of a series of doctors within said tank, and means for causing them to bear yieldingly upon the screening member.
17. In a pulp-washer the combination with 20 a tank and a vertical cylindrical screening member therein and means whereby said screening member is rotated, of a series of horizontal partitions dividing the space be- 25 tween the screening member and the wall of the tank into a series of vertical stages, and a series of flexible packing-rings carried by such partitions and bearing upon the screening member.
18. In a pulp-washer, a vertical cylindrical screening member having an exhaust-passage leading from the interior thereof, and means for adjusting the resistance to the substance flowing through the said exhaust-passage. 30
19. In a pulp-washer, a vertical cylindrical screening member having an exhaust-passage leading from the interior thereof, means for adjusting the resistance to the substance flowing through the said exhaust-passage, and 35 means for maintaining the adjusted resistance.
20. In a pulp-washer, a vertical cylindrical screening member adapted to have a washing fluid flow therethrough, means for adjusting the resistance to the fluid flowing through the 40 screening member, and means for maintaining the degree to which the resistance is adjusted.
21. In a pulp-washer the combination with 45 a tank, of a hollow screening member within such tank, a series of partitions disposed a short distance from one another within the tank, each of such partitions having an opening and the openings of a series being disposed in different positions, an exhaust-passage leading from the interior of the screening member, an intake-pipe leading to one end of the washer and having a valve, and a discharge-pipe leading from the opposite end for the purpose set forth.
22. In a pulp-washer, the combination with 50 a tank, of a hollow screening member within such tank, a series of partitions disposed a short distance from one another within the tank and means supplementing such partitions 55 and closing the spaces between the interior of the tank and the exterior of the screening member, each of such horizontal partitions having an opening and the openings of the series being disposed in different positions, a series of transverse partitions extending be- 60 tween the first-mentioned partitions adjacent to the openings therein and dividing each opening from the one next to it, a series of doctors extending between the annular partitions to which they are pivotally connected, a 65 series of springs yieldingly maintaining the doctors in bearing relation with the screening-cylinder, means for rotating one of said parts, the screening member or the series of doctors, relatively to the other, an exhaust- 70 passage leading from the interior of the screening member, an intake-pipe leading to one end of the washer and having a valve, and a discharge-pipe leading from the opposite end for the purpose set forth.
23. In a pulp-washer the combination with 75 a tank, of a hollow screening member within such tank, a series of annular partitions disposed a short distance from one another within the tank and means supplementing the partitions and closing the space between the interior of the tank and the exterior of the screening member, each of such annular partitions having an opening and the openings of the series being disposed in different angular positions, a series of partitions extending transversely to and between the first-mentioned partitions adjacent to the openings 80 therein and dividing each opening from the one next to it, a series of doctors extending between the annular partitions to which they are pivotally connected, a series of springs yieldingly maintaining the doctors in bearing relation with the screening-cylinder, means for rotating one of said parts, the screening member or the series of doctors, relatively to the other, an exhaust- 85 passage leading from the interior of the screening member, an intake-pipe leading to one end of the washer and having a valve, and a discharge-pipe leading from the opposite end for the purpose set forth.
24. In a pulp-washer the combination with 90 a tank, of a vertical cylindrical screening member within such tank, a series of annular partitions disposed a short distance above one another within the tank and means supplementing the plates and closing the spaces between the interior of the tank and the exterior of the screening member, each of such annular partitions having an opening and the openings of the series being disposed in different angular positions, a series of vertical partitions extending between the partitions adjacent to the openings therein and dividing each opening from the one next to it, means for supporting such annular partitions, a series of doctors extending between the annular partitions to which they are pivotally connected, a series of springs yieldingly maintaining the doctors in bearing relation with the screening-cylinder, means for rotating one of said parts, the screening member or the series of doctors, relatively to the other, an exhaust-passage leading from the interior of the screening member, an intake-pipe leading to one end of the washer and having a valve, and a discharge-pipe leading from the opposite end for the purpose set forth.
25. In a pulp-washer the combination with 100 a tank, of a vertical cylindrical screening member within such tank, a series of annular partitions disposed a short distance above one another within the tank and means supplementing the plates and closing the spaces between the interior of the tank and the exterior of the screening member, each of such annular partitions having an opening and the openings of the series being disposed in different angular positions, a series of vertical partitions extending between the partitions adjacent to the openings therein and dividing each opening from the one next to it, means for supporting such annular partitions, a series of doctors extending between the annular partitions to which they are pivotally connected, a series of springs yieldingly maintaining the doctors in bearing relation with the screening-cylinder, means for rotating one of said parts, the screening member or the series of doctors, relatively to the other, an exhaust-passage leading from the interior of the screening member, an intake-pipe leading to one end of the washer and having a valve, and a discharge-pipe leading from the opposite end for the purpose set forth.

5 nected, a series of springs yieldingly maintaining the doctors in bearing relation with the screening - cylinder, means for rotating one of the said parts, which parts consist of the screening member and the series of doctors, relating to the other, an exhaust or discharge pipe leading from the interior of the screening member, an intake-pipe leading to the lowermost stage of the washer and having 10 a valve, and a discharge-pipe leading from the uppermost stage for the purpose set forth.

25. In a pulp-washer the combination with a tank, of a vertical cylindrical screening member within such tank, a series of annular partitions disposed a short distance above one another within the tank and means supplementing the partitions and closing the spaces between the interior of the tank and the exterior of the screening member, each of such annular 20 partitions having an opening and the openings of the series being disposed in different angular positions, a series of vertical partitions extending between the partitions adjacent to the openings therein and dividing each opening from the one next to it, a ring on the interior of the tank for supporting the lowermost annular partitions, and a series of distance-pieces supported by each horizontal portion and supporting the partition next 25 above it, a series of doctors extending between the annular partitions to which they are pivotally connected, a series of springs yieldingly maintaining the doctors in bearing relation with the screening-cylinder, means for 30 rotating one of the said parts which parts consist of the screening member and the series of doctors, relating to the other, an exhaust or discharge pipe leading from the interior of the screening member, an intake-pipe leading to the lowermost stage of the washer and having a valve, and a discharge-pipe leading from the uppermost stage for the purpose set forth.

26. In a pulp-washer the combination with a tank, of a hollow screening member within such tank, a series of annular partitions disposed a short distance from one another within the tank and means supplementing the partitions and closing the spaces between the interior of the tank and the exterior of the screening member, each of such annular partitions having an opening and the openings of the series being disposed in different angular positions, a series of partitions extending 50 between the partitions adjacent to the openings therein and dividing each opening from the one next to it, a series of doctors extending between the annular partitions to which they are pivotally connected, a series of springs 55 yieldingly maintaining the doctors in bearing relation with the screening-cylinder, means for rotating one of the said parts which parts consist of the screening member and the series of doctors, relatively to the other, a series of 60 perforated annular pipes located one in each

of the stages constituted by the annular partitions, the tank and the screening member, such annular pipes being of sufficient diameter to encircle each stage near the outer periphery thereof, an exhaust or discharge pipe 70 leading from the interior of the screening member, an intake-pipe leading to the lowermost stage of the washer and having a valve, and a discharge-pipe leading from the uppermost stage for the purpose set forth. 75

27. In a pulp-washer the combination with a tank, of a hollow screening member within such tank, a series of annular partitions disposed a short distance from one another within the tank and means supplementing the partitions and closing the spaces between the interior of the tank and the exterior of the screening member, each of such annular partitions having an opening and the openings of the series being disposed in different angular positions, a series of partitions extending between the plates adjacent to the openings therein and dividing each opening from the one next to it, a series of doctors extending between the annular partitions to which they are pivotally connected, a series of springs yieldingly maintaining the doctors in bearing relation with the screening-cylinder, means for rotating one of the said parts which parts consist of the screening member and the series 95 of doctors, relatively to the other, a series of perforated annular pipes located one in each of the stages constituted by the annular partitions, the tank and the screening member, such annular pipes being of sufficient diameter to encircle each stage near the outer periphery thereof, a feed-pipe common to and feeding all the annular pipes of such series, a series of valves controlling the communications between such common feed-pipe and the 100 annular pipes, an exhaust or discharge pipe leading from the interior of the screening member, an intake-pipe leading to the lowermost stage of the washer and having a valve, and a discharge-pipe leading from the uppermost stage for the purpose set forth. 105

28. In a pulp-washer the combination with a tank, of a hollow screening member within such tank, a series of annular partitions disposed a short distance from one another within the tank and means supplementing the partitions and closing the spaces between the interior of the tank and the exterior of the screening member, each of such annular partitions having an opening and the openings of the series being disposed in different angular positions, a series of partitions extending between the partitions adjacent to the openings therein and dividing each opening from the one next to it, a series of doctors extending 115 between the annular plates to which they are pivotally connected, a series of springs yieldingly maintaining the doctors in bearing relation with the screening-cylinder, means for rotating one of the said parts which parts 120 consist of the screening member and the series of perforated annular pipes located one in each 125

- consist of the screening member and the series of doctors, relatively to the other, a series of perforated annular pipes located one in each of the stages constituted by the annular partitions, the tank and the screening member, such annular pipe being of sufficient diameter to encircle each stage near the outer periphery thereof, a series of devices causing jets to project from such annular pipes toward the doctors, a feed-pipe common to and feeding all the annular pipes of such series, a series of valves controlling the communications between such common feed-pipe and the annular pipes, an exhaust or discharge pipe leading from the interior of the screening member, an intake-pipe leading to the lowermost stage of the washer and having a valve, and a discharge-pipe leading from the uppermost stage for the purpose set forth.
29. In a pulp-washer the combination with a tank, of a hollow screening member within such tank, a series of annular partitions disposed a short distance from one another within the tank and of a width to extend from the interior of the tank to within close proximity to the screening member, a series of flexible packing-rings carried by the inner periphery of the annular partitions and bearing upon the screening member, each of such annular plates having an opening and the openings of the series being disposed in different angular positions, a series of partitions extending between the partitions adjacent to the openings therein and dividing each opening from the one next to it, a series of doctors extending between the annular partitions to which they are pivotally connected, a series of springs yieldingly maintaining the doctors in bearing relation with the screening-cylinder, means for rotating one of the said parts which parts consist of the screening member and the series of doctors, relatively to the other, an exhaust or discharge pipe leading from the interior of the screening member, an intake-pipe leading to the lowermost stage of the washer and having a valve, and a discharge-pipe leading from the uppermost stage for the purpose set forth.
30. In a pulp-washer the combination with a tank, of a hollow screening member within such tank, a series of annular partitions disposed a short distance from one another within the tank and means supplementing the partitions and closing the spaces between the interior of the tank and the exterior of the screening member, each of such annular partitions having an opening and the openings of the series being disposed in different angular positions, a series of partitions extending between the partitions adjacent to the openings therein and dividing each opening from the one next to it, a series of doctors extending between the annular partitions to which they are pivotally connected, a series of springs yieldingly maintaining the doctors in bearing relation with the screening-cylinder, means for rotating one of the said parts which parts consist of the screening member and the series of doctors, relatively to the other, an exhaust or discharge pipe leading from the interior of the screening member, such exhaust or discharge pipe being adjustable to locate

relation with the screening-cylinder, means for rotating one of the said parts which parts consist of the screening member and the series of doctors, relatively to the other, an exhaust or discharge pipe leading from the interior of the screening member, such exhaust or discharge pipe being adjustable to locate its discharge end at different heights, an intake-pipe leading to the lowermost stage of the washer and having a valve, and a discharge-pipe leading from the uppermost stage for the purpose set forth.

31. In a pulp-washer the combination with a tank, of a hollow screening member within such tank, a series of annular partitions disposed a short distance from one another within the tank and means supplementing the partitions and closing the spaces between the interior of the tank and the exterior of the screening member, each of such annular partitions having an opening and the openings of the series being disposed in different angular positions, a series of partitions extending between the plates adjacent to the openings therein and dividing each opening from the one next to it, a series of doctors extending between the annular partitions to which they are pivotally connected, a series of springs yieldingly maintaining the doctors in bearing relation with the screening-cylinder, means for rotating one of the said parts which parts consist of the screening member and the series of doctors, relatively to the other, an exhaust or discharge pipe leading from the interior of the screening member, an automatically-variable valve controlling the said exhaust or discharge pipe, an intake-pipe leading to the lowermost stage of the washer and having a valve, and a discharge-pipe leading from the uppermost stage for the purpose set forth.

32. In a pulp-washer the combination with a tank, of a hollow screening member within such tank, a series of annular partitions disposed a short distance from one another within the tank and means supplementing the partitions and closing the spaces between the interior of the tank and the exterior of the screening member, each of such annular partitions having an opening and the openings of the series being disposed in different angular positions, a series of partitions extending between the partitions adjacent to the openings therein and dividing each opening from the one next to it, a series of doctors extending between the annular partitions to which they are pivotally connected, a series of springs yieldingly maintaining the doctors in bearing relation with the screening-cylinder, means for rotating one of the said parts which parts consist of the screening member and the series of doctors, relatively to the other, an exhaust or discharge pipe leading from the interior of the screening member, such exhaust or discharge pipe being adjustable to locate

its discharge end at different heights, an automatically-variable valve controlling the said exhaust or discharge pipe, an intake-pipe leading to the lowermost stage of the washer and having a valve, and a discharge-pipe leading from the uppermost stage for the purpose set forth.

33. In a pulp-washer the combination with a vertical cylindrical tank, of a vertical cylindrical screening member within such tank and having its upper and lower ends closed, the closed upper end having an opening therein, means whereby said screening member is rotated, a series of horizontal annular partitions disposed a short distance above one another within the tank and of a width to extend from the interior of the tank to within close proximity to the screening member, a series of flexible packing-rings carried by the inner periphery of the annular plates and bearing upon the screening member, each of such annular partitions having an opening and the openings of the series being disposed in different angular positions, a series of vertical partitions extending between the horizontal partitions adjacent to the openings therein and dividing each opening from the one next to it, means for supporting such annular partitions, a series of doctors extending between the annular partitions to which they are pivotally connected, a series of springs yieldingly maintaining the doctors in bearing relation with the screening-cylinder, a series of perforated annular pipes located one in each of the stages constituted by the annular partitions, the tank and the screening member, such annular pipes being of sufficient diameter to encircle each stage near the outer periphery thereof, a series of nozzles projecting from such annular pipe toward the doctors, a feed-pipe common to and feeding all the annular pipes of such series, a series of valves controlling the communications between such common feed-pipe and the annular pipes, an exhaust or discharge pipe leading from the interior of the screening member, such exhaust or discharge pipe being adjustable to locate its discharge end at different heights, an automatically-variable valve controlling the said exhaust or discharge pipe, an intake-pipe leading to the lowermost stage of the washer and having a valve, and a discharge-pipe leading from the uppermost stage for the purpose set forth.

34. In a pulp-washer the combination with a vertical cylindrical tank, of a vertical cylindrical screening member within such tank and having its upper and lower ends closed, the closed upper end having an opening therein, means whereby said screening member is rotated, a series of horizontal partitions disposed a short distance above one another within the tank and of a width to extend from the interior of the tank to within close proximity to the screening member, each of such

annular partitions having an opening and the openings of the series being disposed in different angular positions, a series of vertical partitions extending between the horizontal partitions adjacent to the openings therein and dividing each opening from the one next to it, means for supporting such annular partitions, a series of doctors extending between the annular partitions to which they are pivotally connected, a series of springs yieldingly maintaining the doctors in bearing relation with the screening-cylinder, a series of perforated annular pipes located one in each of the stages constituted by the annular partitions, the tank and the screening member, such annular pipes being of sufficient diameter to encircle each stage near the outer periphery thereof, a series of nozzles projecting from such annular pipe toward the doctors, a feed-pipe common to and feeding all the annular pipes of such series, a series of valves controlling the communications between such common feed-pipe and the annular pipes, an exhaust or discharge pipe leading from the interior of the screening member, such exhaust or discharge pipe being adjustable to locate its discharge end at different heights, an automatically-variable valve controlling the said exhaust or discharge pipe, an intake-pipe leading to the lowermost stage of the washer and having a valve, and a discharge-pipe leading from the uppermost stage for the purpose set forth.

35. In a pulp-washer the combination with a tank, of a hollow screening member within such tank, means whereby said screening member is rotated, a series of annular partitions disposed a short distance above one another within the tank and of a width to extend from the interior of the tank to within close proximity to the screening member, a series of flexible packing-rings carried by the inner periphery of the annular partitions and bearing upon the screening member, each of such annular partitions having an opening and the openings of the series being disposed in different angular positions, a series of vertical partitions extending between the partitions to the openings therein and dividing each opening from the one next to it, a ring on the interior of the tank for supporting the lowermost annular partitions, and a series of distance-pieces supported by each partition and supporting the plate next above it, a series of doctors extending between the annular partitions to which they are pivotally connected, a series of springs yieldingly maintaining the doctors in bearing relation with the screening-cylinder, a series of perforated annular pipes located one in each of the stages constituted by the annular partitions, the tank and the screening member, such annular pipes being of sufficient diameter to encircle each stage near the outer periphery thereof, a series of nozzles projecting from such annular

- pipes toward the doctors, a feed-pipe common to and feeding all the pipes of such series, a series of valves controlling the communications between such common feed-pipe and the 5 annular pipes, an exhaust or discharge pipe leading from the interior of the screening member, such exhaust or discharge pipe being adjustable to locate its discharge end at different heights, an automatically-variable 10 valve controlling the said exhaust or discharge pipe, an intake-pipe leading to the lowermost stage of the washer and having a valve, and a discharge-pipe leading from the uppermost stage for the purpose set forth.
- 15 36. In a pulp-washer the combination with a tank, of a vertical cylindrical screening member within such tank, means whereby said screening member is rotated, a series of annular partitions disposed a short distance above 20 one another within the tank and of a width to extend from the interior of the tank to within close proximity to the screening member, a series of flexible packing-rings carried by the inner periphery of the annular partitions and bearing upon the screening member, each of such annular partitions having an opening and the openings of the series being disposed in different angular positions, a series of vertical partitions extending between the 25 30 plates adjacent to the openings therein and dividing each opening from the one next to it, a ring on the interior of the tank for supporting the lowermost annular plate, and a series of distance-pieces supported by each plate and supporting the partitions next above it, a series of doctors extending between the annular partitions to which they are pivotally connected, a series of springs yieldingly maintaining the doctors in bearing relation with 35 40 the screening-cylinder, a series of perforated annular pipes located one in each of the stages constituted by the annular partitions, the tank and the screening member, such annular pipes being of sufficient diameter to encircle each stage near the outer periphery thereof, a series of nozzles projecting from such annular pipes toward the doctors, a feed-pipe common to and feeding all the annular pipes of such series, a series of valves controlling the 45 50 communications between such common feed-pipe and the annular pipes, an exhaust or discharge pipe leading from the interior of the screening member, such exhaust or discharge pipe being adjustable to locate its discharge end at different heights, an automatically-variable 55 valve controlling the said exhaust or discharge pipe, an intake-pipe leading to the lowermost stage of the washer and having a valve, and a discharge-pipe leading from the uppermost 60 stage for the purpose set forth.
37. In a pulp washer or condenser the com-

bination with a vertical cylindrical tank, of a vertical cylindrical screening member within such tank, means whereby said screening member is rotated, a series of horizontal partitions disposed a short distance above one another within the tank and of a width to extend from the interior of the tank to within close proximity to the screening member, a series of flexible packing-rings carried by the 65 inner peripheries of the horizontal annular partitions and bearing upon the screening member, each of such horizontal annular partitions having an opening and the openings of the series being disposed in different 70 angular positions, a series of vertical partitions extending between the horizontal partitions adjacent to the openings therein and dividing each opening from the one next to it, a ring on the interior of the tank for 75 supporting the lowermost annular partitions, and a series of distance-pieces supported by partitions and supporting the plate next above it, a series of doctors extending between the annular partitions to which they 80 are pivotally connected, a series of springs yieldingly maintaining the doctors in bearing relation with the screening-cylinder, a series of perforated annular pipes of progressively-decreasing capacity from the bottom to the 85 top and located one in each of the stages constituted by the annular partitions the tank and the screening member, such annular pipes being of sufficient diameter to encircle each 90 stage near the outer periphery thereof, a series of nozzles projecting from such annular pipes toward the doctors, a feed-pipe common to and feeding all the annular pipes of such series, a series of valves controlling the 95 communications between such common feed-pipe and the annular pipes, an exhaust leading from the interior of the screening member, such exhaust being adjustable to locate its discharge end at different heights, an automatically-variable valve controlling the said 100 exhaust an intake-pipe leading to the lowermost stage of the washer and having a valve, and a discharge-pipe leading from the uppermost stage, for the purpose set forth.

38. In an apparatus for the treatment of pulp by a liquid, a member with which the pulp comes in contact and a doctor submerged in the liquid in the apparatus and adapted to remove the pulp from the side of such member with which the pulp first comes in contact.

In testimony whereof I have affixed my signature in presence of two witnesses.

HORACE GREELEY TURNER.
